DUPLICATE BRIDGE TABLE

Frank de Costa, Jackson Heights, N. Y.

Application June 20, 1932, Serial No. 618,139

10 Claims. (Cl. 273—151)

My invention relates to a device for facilitating the playing of duplicate bridge.

The main purpose of my invention is to construct a bridge table with openings on its upper surface through which playing cards can be withdrawn from a magazine below the upper surface of the table.

A further purpose is to place a series of card-receiving magazines beneath a bridge table, which magazines are adapted to be moved in unison to register the same compartments of the magazines below openings in the table.

A further purpose is to place a series of indications on the upper surface of the movable magazines so that the indications will register through openings in the table.

A further purpose is to provide a bridge table with a series of movable magazines below its upper surface and which are moved coincidentally and whose registration is capable of accurate adjustment.

A further purpose is to construct a playing card magazine with partitions to form compartments, the upper portions of the partitions being recessed to allow for easy removal of the playing cards.

A further purpose is to employ cooperating supporting tracks and rollers for easy manipulation of magazines beneath a table top to register compartments of the magazines below openings in the table top.

A further purpose is to employ a stopping device to control the movement of magazines and hold the magazines in a desired position beneath a table.

A further purpose is to provide a pivoted closure for an enlarged opening in a slot of a bridge table.

Describing in illustration and not in limitation but referring to the drawings,

Figure 1 is a top plan view of my improved duplicate contract bridge table.

Figure 2 is a side elevation of the table shown in Figure 1.

Figure 3 is a sectional top plan view taken on the line 3—3 of Figure 2.

Figure 4 is a longitudinal sectional view taken on the line 4—4 of Figure 1.

Figure 5 is an enlarged fragmentary sectional view taken on the line 5—5 of Figure 1.

Figure 6 is a transverse sectional view taken on the line 6—6 of Figure 5.

Figure 7 is an enlarged transverse sectional view taken on the line 7—7 of Figure 3.

Figure 8 is an enlarged fragmentary longitudinal

sectional view taken on the line 8—8 of Figure 3.

Figure 9 is an enlarged perspective view of one of the partitioned magazines used in the construction of my improved table.

Figure 10 is a fragmentary enlarged top plan view of a portion of my improved table showing a closure for an enlarged opening in the card withdrawal slot.

Figure 11 is a fragmentary sectional view taken on the line 11—11 of Figure 10.

I have preferred to show one form only of the different forms that might be selected to illustrate my invention, selecting a form however, that I have found to be efficient in use and practical in construction which well illustrates the principles involved.

In the drawings I show a rectangular table 15 having a top 16, sides 17 and legs 18. The table top 16 is provided with slotted openings 19, 20, 21 and 22 near the edge of the table and each in front of one of the four players, here in the approximate middle of one of the four sides.

Below the table top 16, I place a plurality of partitioned card magazines 23, 24, 25 and 26. These card magazines are supported, in the illustration shown, by angle irons 27 and 27' upon rollers 28 mounted in bearing strips 29 upon the sides 17 of the table, and from angle iron bearings 30 beneath the table top 16.

The sets of cards in the different magazines are separated by divisions or partitions 31 forming compartments 32 in which the individual hands of cards lie in a vertical position with their upper edges exposed so that in any given position of the magazines, four hands 33 from the same decks are exposed beneath the openings 19, 20, 21 and 22. They are intended to be used for play together. The hands exposed are determined, of course, by the compartments 35 which correspond with these openings at the same time. The hands are shown in Figure 1.

The card magazines are moved to registry beneath the slots in the table top by means of a knob 34 positioned on one side of and outside the table. The knob is fastened to a shaft 35 extending interiorly of the table and the shaft carries a sprocket 36. The sprocket 36 drives a chain 37 which is connected at its two ends 38 and 39 to the card magazines 23 and 24. In one corner the chain 37 passes about a sprocket 40 which is pivoted at 41 in a suitable bearing 42.

Cable ends 43 and 44 are fastened at 45 to the card magazines 23 and 24 and the cable 46

passes about pulleys 46, 47 and 48. The pulleys are mounted in the corners of the table upon shafts 49 turning in bearings 50.

The attachment of the cable to the card magazines can be made in various ways and I have shown one simple form of connecting the cable to the card magazines by the use of set screws 51. The cable passes through apertured blocks 52 which are secured to each of the magazines.

As shown in Figures 5 and 6 the shaft 35 projects outwardly through the side 17 of the table which side 17 provides a bearing 53 for the shaft 35. A recess 54 is provided in the side 17 of the table 15 to receive a spring 55, and a triangular block 56 fastened to the shaft 35 is also inserted in the recess. A knob 34 is pinned at 57 to the shaft 35.

Each rotation of the shaft 35 corresponds with the passage of a definite and complete number of compartments of the magazines passing the openings in the tables. This facilitates convenient stoppage of the magazines so that in whatever positions they stop one compartment will lie in central position below each opening. The mechanism provided for insuring stoppage for proper compartment position each time lies in a cam 56 rotatable with the shaft 35 engaging with the spring 55. The number of positions on the cam will of course correspond with the number of compartment distances for which the magazines are advanced by each rotation of the cam.

The cam shown is triangular providing three flat surfaces 58 which in turn engage and rest against the spring 55. The flats make it possible for the operator of the knob to feel the positions of registration without necessity for looking for them and to bring the compartments to registry against the action of the spring engaging the flat of the cam which avoids accidental displacement of the magazines, and carrying the cam to position when it is not fully turned and bringing it back from positions of slight over movement.

It will be recognized that the shaft 35 need not be made a unit but that some full stroke device having positions corresponding with the compartment positions is quite desirable and is supplied both cheaply and conveniently by the mechanism shown.

When the triangular cam is turned, one end of the spring slides outwardly. It is desirable to fasten the other end of the spring, as at 55', to the inner surface of the recess to prevent bodily displacement of the spring from its position in the recess 54.

The next step by one of the players is to turn the knob and cause the next compartment of each of the magazines below the slots in the upper surface of the table to register to allow for withdrawal from the compartments of the magazines a different hand from that previously played.

It will be obvious that accurate registry of the playing cards beneath the slots in the upper surface of the table is essential for conveniently withdrawing the proper hands of cards from the magazines. It is for this reason that I have provided the triangular stop 56 as I have found this to be an accurate registering device.

The angle irons 27 which are secured to the magazines have their upper surfaces provided with a series of indications which register

through the slots in the upper surface of the table.

In playing duplicate bridge, one hand is played to its conclusion by each player, and then the deck is put aside for subsequent use, keeping the hands of the players separated. The same procedure is followed for the subsequent hands using a different deck each time, until the players have gone through a predetermined number (usually 16 or 32). The decks are then 10 replayed giving the hands originally played by one set of partners to the opposite set of partners.

With the system of play now in use, the hands of each deck are filed away in a compartment 15 on a board, the board being taken out and the hands withdrawn the next time that deck is to be played.

My device is effectively an automatic filing system for receiving the hands immediately after 20 they have been played, for supplying the next hands to be played, and for furnishing the hands over again to the opposite sets of partners after the full number of decks have been played.

The hands of the different decks are initially dealt out and placed in the compartments of the magazine. They are then ready for withdrawal by the four players. After each of the hands of any deck has been played the hands 30 are replaced in the compartments of the magazine from which they were removed.

The surface of the angle iron 27 carries indications 59 in the form of numerals to identify the different decks to which belong the hands 35 to be placed in the magazine. This allows replaying of the hands by opposite partners, the players changing positions at the board to effect the change.

I find it desirable to provide the numbers representing the decks on one magazine only preferably on the magazine nearest the operator.

Another angle iron 27' carries letters for identification of the dealer and to designate whether or not hands are vulnerable and if so 45 which hands.

The letters shown on one row indicate positions, as N, E, S and W. The remaining row of letters indicates what hands are or are not vulnerable and are interpreted, O, that none 50 are vulnerable; B, that both are vulnerable; NS, that north and south are vulnerable; and EW, that east and west are vulnerable.

I provide mechanism whereby the magazines, arranged beneath the table top, can be accurately set initially or subsequently adjusted if the cable should stretch.

The compartments may thus be set with respect to the slots in the table. For this reason I attach the cable at 45 to the magazines by 60 set screws 51, which permit the necessary setting and any desired adjustment.

A turn buckle 60 provides a simple arrangement for taking up the slack in the cable if the cable should stretch.

The table legs 18 are preferably hinged at 61 although it is not necessary that they should be hinged as it would not affect my invention in any way.

Each of the slots 19, 20, 21 and 22 is enlarged 70 to form a circular opening 19', 20', 21' and 22' to allow for grasping the cards to withdraw them from the magazine.

I find it desirable to provide a closure for the enlarged openings 19', 20', 21' and 22' to pre- 75

vent the cards from falling out or to protect them from dust. I have therefore supplied disc closures 62 having outwardly extending projections 63. The discs are pivoted to the under side of the table at 64 near to the openings. Upwardly extending plugs 65 are fastened to the discs 62 to act as stops to limit the amount of movement of the discs when they are swung into closed or open position. In Figure 10, I show in full lines the disc in its position of closure and in dot and dash lines in its open position.

I also find it desirable to provide a slidable closure 62' having an upwardly turned end 62'. This closure will enable the user to cover the indications upon the upper surface of the flange 27' when desired. The upwardly turned end 62' provides a convenient finger hold to move the closure 62'.

20 I show a chain guide 66 to keep the chain in place upon the sprocket 36.

The magazines are recessed at 23' to allow for easy grasping of the cards for withdrawal.

It will be evident that the broad features of my invention do not concern the character of division walls between the compartments, the character of the supports by which the magazines are held and guided nor the mechanism by which they are concurrently operated and held in registering relation so that the corresponding hands of the same deck each time appear below the openings in the table when these hands are to be played. It is important that the cards be supported in vertical planes and that in each magazine the hands from different decks be separated so as to be individually accessible without confusion with adjoining hands.

It will be further evident that there is an inter-relation between the various indications presented and the mechanical features of the individual magazines notwithstanding that the indicators would operate with other mechanical constructions.

It will be further evident that the straight line movement of the magazine passed the point at which the hands are to be successively withdrawn and replaced permits rectangular compartments as distinguished from radial compartments, for example.

50 In view of my invention and disclosure variations and modifications to meet individual whims or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters

60 Patent is:

1. A card table having a top and openings in the top at intervals corresponding to the positions of players about the table, a plurality of magazines each presenting card compartments adapted to be brought in line with the openings, guiding and supporting means for the magazines, a flexible connection uniting the magazines, means for adjusting the position of the magazines along the flexible connection, guides for the flexible connection at the corners of the table and means for lengthwise moving the flexible connection to cause the magazines to move in unison beneath the respective openings.

70 2. A card table having a top and openings in the top corresponding to positions of players,

a plurality of magazines located beneath the table top and in position to provide compartments for cards on edge corresponding to successive hands of decks of cards to be played, means for mounting and guiding the magazines to travel beneath the openings and flexible connections between the magazines causing them to move in unison and sprocket and chain means for moving the flexible connections.

3. A card table top having openings at intervals corresponding with the positions of the players, a plurality of magazines supported beneath the top, rollers for the magazines, angle irons secured to the magazines and engaging the rollers, flexible connections between the magazines adjustable with respect to the magazines and means for moving the flexible connections.

4. In a card table top having slots in the top, magazines below the upper surface of the top having compartments adapted to register beneath the slots in the table, a chain and cable connecting the magazines, a sprocket and rollers about which the chain and cables rotate, magazine adjusting means on the cable, a turn buckle for taking up slack in the cable and a knob shaft, 20 sprocket on the shaft adapted to mesh with the chain to move the magazines.

5. A table top having slots, magazines below the upper surface of the top transversely movable with respect to the slots, cable adjustably 30 connected to the magazines, rollers about which the cables pass, chain and sprocket connection between the ends of the cables and a triangular cam and spring connection secured on one of the sprockets for controlling the registry of the 35 magazine below the slots in the table.

6. A card table of rectangular form having four openings through the table top, one on each side of the table, four separate partitioned magazines, each beneath the table top and each adjacent one of the four sides of the table and moving longitudinally of that side of the table, guideways for the magazines and means for concurrently moving the magazines in their guideways, whereby successive spaces between 40 partitions in the magazines will match with the openings and the positions of the magazines with respect to the openings will be correlated.

7. A card table of generally rectangular form having four openings through the top of the table, one adjacent each side, four separate partitioned magazines, each movable longitudinally of one side of the table and capable of having the spaces between the partitions match with one of the openings, guideways for each magazine, 50 flexible connections extending from one magazine to the next magazine around the table and attached to each magazine and means for changing the directions of the flexible connections at the corners of the table.

8. A card table of rectangular form having a top provided with four openings, one adjacent each side of the table, four separate partitioned magazines, guideways for each magazine making the magazine movable longitudinally of one side 65 of the table to positions in which the spaces between successive partitions of the magazine align with the opening for that magazine, flexible connections from one magazine to another so that all magazines will move as a unit, means for changing the direction of the flexible connections at the corners of the table and means for feeding the flexible connections forward and thereby moving the magazines.

9. In a card table, four magazines positioned 75

like the sides of a square, and means for concurrently moving the magazines toward the successive corners of the square, whereby one magazine travels into a portion of the space formerly occupied by another magazine.

5. 10. In a card table, four separate partitioned magazines, one positioned to correspond with each of the points of the compass, a card table

having openings equally spaced around its perimeter, each opening cooperating with a magazine, guiding means for the magazines attached to the table, an endless flexible connection following the general external contour of the table 5 and secured to the magazines and means for progressing the flexible connection.

FRANK DE COSTA.
